UNITED STATES PATENT OFFICE.

JACOB C. EICHHORN, OF DETROIT, MICHIGAN, ASSIGNOR TO VICTOR JAR COMPANY, OF DETROIT, MICHIGAN, A CORPORATION OF MICHIGAN.

DESIGN FOR A JAR OR RECEPTACLE.

45,801.

Specification for Design.

Patented May 19, 1914.

Application filed March 18, 1914. Serial No. 825,698. Term of patent 3½ years.

To all whom it may concern:

Be it known that I, JACOB C. EICHHORN, a citizen of the United States of America, residing at Detroit, in the county of Wayne and State of Michigan, have invented a new, original, and ornamental Design for a Jar or Receptacle, of which the following is a specification, reference being had therein to the accompanying drawing, forming part thereof.

The figure is a perspective view of a jar showing my new design.

I claim:—

The ornamental design for a jar or receptacle as shown.

JACOB C. EICHHORN.
